UNITED STATES PATENT OFFICE.

HARLEY C. MOULTON, OF DORCHESTER, MASSACHUSETTS, ASSIGNOR TO ARBETTER FELLING MACHINE COMPANY, OF BOSTON, MASSACHUSETTS, A CORPORATION OF MAINE.

BLINDSTITCH SEWING-MACHINE.

1,255,628.

Specification of Letters Patent.

Patented Feb. 5, 1918.

Application filed January 20, 1915. Serial No. 3,343.

To all whom it may concern:

Be it known that I, HARLEY C. MOULTON, a citizen of the United States, and resident of Dorchester, county of Suffolk, State of Massachusetts, have invented an Improvement in Blindstitch Sewing-Machines, of which the following description, in connection with the accompanying drawing, is a specification, like characters on the drawing 10 representing like parts.

This invention relates to improvements in blind stitch sewing machines for felling, padding, and the like and particularly to a novel form of bender mechanism operable 15 in connection with a sewing machine having a reciprocating and laterally vibrating needle.

In the usual blind stitch sewing machine having a reciprocating needle and supplemental stitch forming mechanism when felling the bender is actuated upon every other stitch to raise the base layer of cloth into the path of the needle so that the needle will penetrate and emerge from the upper 25 surface of the base layer without passing through the same. In alternating series of stitches the needle is shogged and upon its penetrating stroke passes over the base layer entering the superimposed layer beneath and 30 back from the edge and emerging from the upper surface or from the edge thereof. In such case the bender remains depressed beneath the work support during the formation 35 of the stitch in the superimposed layer.

The present invention contemplates the production of blind stitching seams in which the needle in one series of stitches penetrates and emerges from the upper face of the base 40 layer of fabric without passing entirely through the fabric, and upon the alternating series of stitches penetrates and emerges from the upper face of the superimposed fabric, the seam thus produced being concealed by folding over the superimposed 45 layer and pressing the same so that the edge of the fold overlies the stitching, thus forming a seam of the type which is commonly used in attaching the bottom of the lining 50 of coats to the body of the coat.

In making the seam by the mechanism disclosed herein the needle is caused first to penetrate the base layer which is thrust upward by the bender for that purpose,

then the needle is shogged laterally so that 55 it will enter the upper surface of the superimposed layer a short distance back from the edge thereof, the base and superimposed layer being thrust upwardly by the bender just sufficiently for this purpose. When the 60 seam is completed the superimposed layer is folded beyond the stitching and pressed so that the threads are entirely concealed.

In order to adapt this mechanism for different classes of work, that is, different 65 thicknesses in the base layer and of the superimposed layer it is essential that means be provided for independently adjusting the bender upon alternate thrusts so that the base layer may be raised to a sufficient height 70 to permit the needle to penetrate well into the same upon one set of stitches and that it be raised to a less height upon the alternate stitches, so that the needle will merely penetrate the superimposed layer. So far 75 as I am aware no mechanism has heretofore been devised which will permit of or provide for the independent adjustment of the thrust of the bender for different or alternate stitches.

One of the objects of this invention therefore is to provide a blind stitch sewing machine having an oscillating and laterally vibrating needle with bender mechanism which is adapted to thrust the bender 85 through the work plate to raise the material which is fed across the work plate into the path of the needle upon each penetrating stroke of the needle, wherein independent means are provided for adjusting the 90 height to which the bender is elevated upon alternate reciprocations.

Another object is to provide means located above the work support for adjusting the respective heights to which the bender 95 may be raised.

Another object of the invention is to provide means for actuating the bender in the manner above described through a toggle mechanism in which the toggle is straightened twice to project the bender through the work support upon each revolution of the driving shaft which operates said bender.

Other objects of the invention and the nature thereof will more fully appear from 105 the following description and the accompanying drawings and will be pointed out in the annexed claims.

The invention is illustrated in the drawings as applied to a blind stitch sewing machine for felling, of the Arbetter type.

Figure 1 is a side elevation of a sewing machine embodying one of the preferred forms of my invention,

Fig. 2 is an end view of a portion of a sewing machine head and needle mechanism and of the bender mechanism aforesaid,

10 Fig. 3 is a vertical sectional view on line 3—3 Fig. 1 looking toward the front end of the machine.

Fig. 4 is an underside plan view of the end of the base plate and the bender mechanism supported thereby.

The sewing machine illustrated in the drawings comprises the usual bed plate 1 having a standard 2 rising therefrom provided with the usual laterally extending 20 arm 3 terminating in the head 4. The arm supports the usual main shaft 5 with its driving pulley 6 and hand wheel 7. The driving shaft is provided at its front end with a disk 8 having an eccentrically disposed stud or pin 9 connected by a universal joint to an arm 11 of a rock shaft 12, to the opposite end of which a collar 13 is attached which carries the needle bar 14 for a curved oscillating needle 15. The rock shaft 12 is journaled in a sleeve 16 connected to an arm 17 of a shaft 18 which is suitably journaled in vertical bearings in the sewing machine head, the shaft 18 being vibrated by suitable mechanism, not shown, to shog 30 the needle laterally for alternate stitches. Suitable complementary stitch forming mechanism may be provided, such as the rotary hook mechanism illustrated in Fig. 2 in which a hook bracket 20 is adjustably secured by a slot and screw connection 21 to an extension 22 depending from the sewing machine head, the hook bracket carrying at its lower end the usual support for the hook 23.

45 As illustrated herein an upper feeding mechanism is provided which consists of a feed dog 24 adjustably secured upon the end of a bar 25 which is pivotally supported by a shaft journaled in a vertical reciprocating bearing 26 and is actuated through 50 a lever 27 by suitable and usual mechanism not shown.

A stationary presser foot 28 suitably secured to a bracket 29 extending downwardly from the sewing machine head provides means for limiting the upward movement of a spring actuated work support 30 and forms one of the members which serve to clamp the work during the stitching operation.

60 The work support 30 is desirably in the form of a substantially rectangular plate carried upon a standard 31 journaled in suitable bearings 32—33 in a bracket 34 65 which is secured by suitable screws 35—36

to flanges 37—38 depending from the under surface of the bed plate adjacent to the edges thereof.

The work support is retained normally in elevated position by means of a helical spring 39 surrounding the standard 31 and resting at its lower end upon the journal 33 and at its upper end bearing upon the under surface of a sleeve 40, having a laterally extending arm 41 which rides within a keeper 70 42. The sleeve 40 is adjustably secured to the standard 31 by a set screw 43 or other suitable fastener. The work support may be lowered through the instrumentality of a knee lever, not shown, connected at one 75 end to the arm 44 of a bell crank lever, the other arm 45 of which is provided with an offset lever 46 having an extension 47 overlying the upper edge of the arm 41 so that upon lateral pressure upon said knee lever 80 the bell crank arm will be rocked in such a manner as to depress the arm 41 and the collar 40 and consequently the standard 31 of the work support.

85 The mechanism thus far disclosed is of a usual character in blind stitch sewing machines of the Arbetter type.

The bender mechanism as illustrated herein comprises a bender 50 mounted in suitable bearings 51, 52 in the bracket 34 95 aforesaid, the bender being normally thrust to upwardly extended position, through a suitable aperture in the work plate, by means of a spring 54 which engages at its upper end the base of the bender and at its lower end rests upon a stand 55. The stand 55 is yieldably supported upon a helical spring 56 which rests upon the end of a hollow screw 58 seated in a boss 53 on the bracket 34. A guiding stem 57 depending from the stand 54 and passing through the aperture in the screw 58 serves to aid in maintaining the stand in proper position while permitting vertical reciprocation thereof.

100 The bender desirably is raised and lowered by toggle mechanism which is actuated through a countershaft carried beneath the base plate of the machine. As illustrated herein a countershaft 60 is journaled in suitable bearings 61 depending from or secured to the under surface of the bed plate, and is provided with a gear 62 meshing with a gear 63 upon a vertical countershaft 64 which has at its upper end a beveled gear 115 65 engaging a similar gear 66 upon the main shaft of the machine.

120 As disclosed herein the gear 62 is twice as large in diameter as the gears 63, 65 and 66, so that the shaft 60 is driven at one revolution to every two revolutions of the main driving shaft.

125 In order to produce a reciprocation of the bender for every penetrating stroke of the needle it is therefore necessary that the tog- 130

gle shall be straightened twice during every revolution of the countershaft 60.

As illustrated in the drawings the bender 50 is provided with an adjustable sleeve 70 secured thereto by a set screw 71 the sleeve having upon its side opposite to said set screw a cylindrical extension or stud 72 by means of which it is connected to the upper end of a toggle link 73, the other toggle link 74 being pivotally connected at its lower end to a stud 75 projecting laterally from an ear 76 upon the stand 55. The stand 55 is also provided with a cylindrical stem 77 journaled in the bearing 78 in the bracket 34 so that the stand 55 is provided with two guide stems, one adjacent to the connection with the toggle link 74 and the other substantially in alinement with the bender. The pivotal joint 79 of the toggle links 73-74 is extended and is connected by an arm 80 to an arm 81 which in turn is connected to the crank 82 extending laterally from the crank disk 83 secured to the end of the shaft 60.

25 In order to give the proper movement to the mechanism illustrated in the drawing the pivotal shaft connecting the arms 80 and 81 is extended and pivotally connected to an arm 85 which is journaled upon a stud 86 projecting laterally from a boss 87 on the inner side of the bracket 34. It is to be understood however that other toggle arrangements may be made whereby the idle arm 85 may be dispensed with.

35 As the shaft 60 rotates the arm 81 causes the oscillation of the toggles through the arm 80 which connects to the pivot 79 of the toggle links 73, 74 so that upon each rotation of the shaft 60 the connection of the toggle links 73, 74 crosses the vertical axial plane of the bender straightening the toggles and thrusting the bender to the uppermost position provided for by said toggle. It will thus be observed that whereas 45 the shaft 60 rotates half as fast as the main driving shaft the toggle is thrust upwardly twice during every revolution of the shaft 60 and consequently the bender is thrust upwardly for every rotation of the main shaft 50 and consequently upon every penetrating stroke of the needle caused thereby.

As before stated it is necessary that the means be provided for regulating the height of the thrust for the respective alternate series of stitches which are laid in the base and superimposed layers respectively and to accomplish this end I have provided means for limiting the upward thrust of the bender upon each straightening of the toggle. This is accomplished in the preferred embodiment of the invention illustrated herein by providing means for limiting the upward movement of the spring supported stand 55 to which the toggle link 74 is pivoted.

The mechanism for limiting the upward movement of the stand 55 during the reciprocation of the bender for its engagement with the main or base layer of fabric is accomplished through the bell crank lever 90 pivotally mounted upon a stud 91 projecting laterally from the rear side of the bracket 34, one end 92 of said bell crank lever projecting over an ear 76 on the stand 55, the other arm 93 of said lever being recessed to receive the lower end of an adjustable stem 94 which may be provided with set nuts 95 to engage the under surface of the arm 93. The stem 94 desirably passes through a boss or sleeve 96 depending from the main frame, and is screw threaded at its upper end to engage a milled nut 97 located above the base plate of the machine. It will be obvious that by turning the milled nut 97 to the right the arm 93 of the bell crank lever will be raised and the limiting end 92 of said lever be depressed so that the bender will not be projected to its full height upon the straightening of the toggle links. Upon the other hand if the milled nut 97 is rotated to the left the arm 93 will be released so that the spring 56 which supports the shelf 55 will raise the stand 55 to a higher position permitting the bender to be thrust to a greater height above the plane of the work support upon the straightening of the toggle.

As before stated it is necessary to provide a separate adjustment for the series of stitches in the superimposed layer so that the bender will not thrust the work to such a high elevation as it does during the stroke of the needle which penetrates the base layer of the fabric. In order to accomplish this result I have provided a special mechanism actuated through the medium of a cam upon the countershaft 60 which will depress the stand 55 upon each alternate straightening of the toggle which operates the bender.

I have also provided means for adjusting the highest position to which the bender may be thrust during such operation. As illustrated herein this mechanism comprises a bell crank lever 100 pivoted upon a stud 101 extending rearwardly from the bracket 34, said lever 100 having an arm 102 extending over a lip 103 projecting laterally from the stand 55. The opposite arm of the bell crank lever is engaged by the end of an adjustable screw seated in the end of an arm 105 of the bell crank lever which comprises a shaft 106 journaled in a suitable bearing in a bracket 34 at one end and in a bracket 107 at the opposite end. The shaft 106 is provided near its opposite end at or adjacent to the bracket 107 with an arm 108 which rests upon the end of a lever 109 which is forked at its opposite end 110 to embrace the flattened end of a stem 111 of an adjust-

ing screw which extends through a rotatable sleeve 112 having an attached central milled nut 113 projecting above the base plate. The central portion of the lever 109 is engaged by a cam 114 secured to the shaft 60 adjacent to the crank disk 78.

A helical spring 115 connected at one end to a stud 116 on the arm 102 of the bell crank lever 100 and at its other end to a stud 117 on the machine frame serves to hold the limiting arm normally out of engagement with the ledge 103 of the stand 55.

It will be obvious that the rotation of the milled sleeve 113 will serve to raise or lower the fulcrum of the lever 109 in respect to the cam disk 114 so that the amplitude of oscillation of the system of levers may be varied and the highest position assumed by the stand 55 during the stroke of the needle in 20 the superimposed layer determined.

In the operation of the machine the adjustments of the bender aforesaid may be regulated by the milled nut 97 so that the bender upon one series of its upward thrusts 25 will bend up a portion of the base layer of the fabric just sufficiently to permit the needle upon its penetrating stroke to enter and emerge from the upper surface of said base layer without passing through the entire 30 layer. Adjustment may also be effected through the milled nut 113 of the mechanism for limiting the uppermost position of the bender upon alternate penetrating strokes so that the bender will raise the base and 35 superimposed layers just sufficiently to permit the oscillating needle upon its alternate strokes to pass through the upper surface or so much as is desirable of the superimposed layer, without penetrating the base layer, 40 so that a blind stitching seam for felling may be formed upon this machine with the bender rising at every penetrating stroke of the needle.

By reason of the ability to vary the thrust 45 of the bender upon every series of movements the lining may be placed upon the bed plate to form the base layer as well as a heavier piece of fabric which is attached thereto.

It will be obvious that the bender may be 50 so adjusted as to project equal distances through the work plate upon each oscillation of the needle or that the bender mechanism may be so adjusted that the bender may be projected a much greater distance upon 55 one series of thrusts than upon the alternate thrusts or may be rendered wholly ineffective upon alternate thrusts thus providing for a wide range of usefulness in blind stitching, padding and the like.

60 It is to be understood that the embodiment of my invention disclosed herein is illustrative merely and not restrictive and that other forms thereof may be constructed within the spirit of my invention.

65 Having thus described my invention, what

I claim as new and desire to secure by Letters Patent is;

1. A sewing machine comprising a work support, a reciprocating needle and complementary stitch forming mechanism located 70 above the work support; means for feeding the work across said work support in advance of each penetrating stroke of the needle, a bender, means for actuating the same and independent means for adjusting the 75 thrust of the bender upon alternate strokes.

2. In a blind stitch sewing machine for felling a superimposed layer upon a base layer, a work support, a reciprocating needle and complementary stitch forming mechanism located above the work support, means 80 for feeding the work across the work support, a bender, means for actuating the same and means for varying the thrust of the bender upon alternate strokes.

3. In a blind stitch sewing machine for felling a superimposed layer upon a base layer, a work support, a reciprocating needle and complementary stitch forming mechanism located above the work support, means 90 for feeding the work across the work support, a bender, means for actuating the same and independently adjustable means for limiting the thrust of the bender upon alternate strokes.

4. In a blind stitch sewing machine for felling a superimposed layer upon a base layer, a work support; a reciprocating needle and complementary stitch forming mechanism located above the work support; means 100 for feeding the work across the work support; means for vibrating the needle to cause the same to reciprocate in different planes; a bender, means for actuating the same upon each penetrating stroke of the needle and 105 means for varying the thrust of the bender upon alternate strokes.

5. In a blind stitch sewing machine for felling a superimposed layer upon a base layer, a work support; a curved oscillating 11 needle and complementary stitch forming mechanism located above the work support; means for feeding the work across the work support; means for vibrating the needle to cause the same to oscillate in different planes; a bender, means for actuating the same upon each penetrating stroke of the needle and 115 means for adjusting the thrust of the bender to present the base layer to the needle to accommodate different thicknesses 12 thereof.

6. In a blind stitch sewing machine for felling a superimposed layer upon a base layer, a work support; a curved oscillating needle and complementary stitch forming 13 mechanism located above the work support; means for feeding the work across the work support; means for vibrating the needle to cause the same to oscillate in different planes; a bender, means for actuating the 14

same upon each penetrating stroke of the needle and independent means for adjusting the height of the alternate thrust of the bender to provide for blind stitching different thicknesses of material in the base layer and also different thicknesses of material in the superimposed layer.

11. A sewing machine comprising a work support; a curved needle and complementary stitch forming mechanism located above the work support; a main shaft and means connected thereto for oscillating said needle upon every rotation of the shaft; a countershaft; means for rotating the same from the main shaft once upon every two revolutions of the main shaft; a bender, a toggle connected to said bender and to a relatively stationary support, means for oscillating the joint of the toggle from said countershaft to cause the toggle to straighten twice during every revolution of said countershaft.

12. A sewing machine comprising a work support; a curved needle and complementary stitch forming mechanism located above the work support; a main shaft and means connected thereto for oscillating said needle upon every rotation of the shaft; a countershaft; means for rotating the same from the main shaft once upon every two revolutions of the main shaft; a bender; a toggle connected to said bender and to a spring supported stand; independent means for adjusting the highest position of said stand upon alternate thrusts of the bender, and means connecting the joint of said toggle to said countershaft to cause the toggle to straighten twice during every revolution of the countershaft.

13. In a sewing machine for felling a superimposed layer upon a base layer, a work support; a curved needle and complementary stitch forming mechanism located above the work support; a main shaft and means connected thereto for oscillating the needle upon every rotation of the shaft; means for vibrating the needle to cause the same to oscillate alternately in different planes to engage the base layer and the superimposed layer respectively; a countershaft, means for rotating the same from said main shaft once upon every two revolutions of the main shaft; a bender; a toggle connected to said bender and a spring supported stand; means actuated from the countershaft for reciprocating the joint of the toggle lever to thrust the bender through the work support twice upon every revolution of said countershaft; means for adjusting the uppermost position of the spring supported stand during the engagement of the bender with the base layer consisting of a lever extending at one end over said stand and the other end connected to a bolt having a milled nut located above the bed plate of the machine.

14. A blind stitch sewing machine for felling comprising a work support, a curved oscillating needle and complementary stitch forming mechanism located upon the work

130

5

same upon each penetrating stroke of the needle and independent means for adjusting the height of the alternate thrust of the bender to provide for blind stitching different thicknesses of material in the base layer and also different thicknesses of material in the superimposed layer.

7. In a sewing machine comprising a work support, a curved oscillating needle and complementary stitch forming mechanism located above the work support; means for feeding the work across the work support; means for vibrating the needle to cause the same to oscillate in different planes; a bender, means for thrusting the same through the work support to present the work to the needle comprising a toggle having one end connected to the bender and the other to a relatively stationary but adjustable supporting stand and means for oscillating the connection of the toggle links across the axial plane of the bender whereby the same will be reciprocated twice during each full oscillation of the toggle.

8. In a blind stitch sewing machine comprising a work support, a curved oscillating needle and complementary stitch forming mechanism located above the work support; means for vibrating the needle to cause the same to oscillate in different planes, a bender, a toggle for actuating the same having one arm connected to said bender and the other arm to a yieldable support, means to actuate said toggle and means to limit the upward position of the toggle support whereby the height of thrust of the bender will be adjusted.

9. In a blind stitch sewing machine comprising a work support, a curved oscillating needle and complementary stitch forming mechanism located above the work support, means for vibrating the needle to cause the same to oscillate in different planes, a bender, a toggle for actuating the same having one arm connected to said bender and the other arm to a yieldable supporting stand, means for oscillating the joint of the toggle upon opposite sides of the vertical axial plane of the bender and independent means for limiting the uppermost position of the yieldable support upon each alternate reciprocation of the toggle.

10. A sewing machine comprising a work support, a curved needle and complementary stitch forming mechanism located above the work support; a main shaft and means connected thereto for oscillating said needle upon every rotation of the shaft; a countershaft; means for rotating the same from said main shaft once upon every two revolutions of the main shaft; a bender and means connecting said bender to said countershaft for causing the bender to be reciprocated twice during each rotation of said countershaft and in synchronism with

- support; a main shaft and means connected thereto for oscillating said needle upon every rotation of said main shaft; a countershaft; means for rotating the same from the main shaft once upon every two revolutions of the main shaft; a bender; a toggle connected to said bender and to a spring supported stand; means for actuating said toggle to cause the bender to be thrust through the work support twice during each rotation of said countershaft and in synchronism with the oscillation of the needle; means for causing a different degree of thrust by said bender during alternating stitches comprising a lever engaging said stand, a cam upon said countershaft and means engaged by said cam for operating said lever to depress the stand a predetermined amount.
15. In a sewing machine for felling a superimposed layer upon a base layer, a work support; a curved needle and complementary stitch forming mechanism located above the work support; a main shaft and means connected thereto for oscillating the needle upon every rotation of the shaft; means for vibrating the needle to cause the same to oscillate alternately in different planes to engage the base layer and the superimposed layer respectively; a countershaft; means for rotating the same from said main shaft once
- upon every two revolutions of the main shaft; a bender; a toggle connected to said bender and to the spring supported stand; means actuated from the countershaft for reciprocating the joint of the toggle lever to thrust the bender through the work support twice upon every revolution of said countershaft; means for adjusting the uppermost position of the bender during its engagement with the work to position the superimposed layer in the path of the needle comprising a series of levers, one of which engages the spring supported stand and another of which is pivotally mounted upon a stem adjustable by a milled nut extending through the bed plate of the machine; and a cam upon said countershaft adapted to engage the last mentioned lever, whereby the stand will be depressed a predetermined amount during the actuation of the bender to present the superimposed layer to the needle.
20. In testimony whereof, I have signed my name to this specification, in the presence of two subscribing witnesses.
